United States Patent Office.

DANIEL LOMBARD, OF BOSTON, MASSACHUSETTS.

Letters Patent No. 73,819, dated January 28, 1868.

IMPROVED MACHINE FOR HULLING COFFEE.

The Schedule referred to in these Letters Patent and making part of the same.

TO ALL WHOM IT MAY CONCERN:

Be it known that I, DANIEL LOMBARD, of Boston, in the county of Suffolk, and State of Massachusetts, have invented a new and useful Improvement in Machines for Hulling Coffee, of which the following is a full, clear, and exact description, reference being had to the accompanying drawings, making a part of this specification, in which—

Figure 1 represents a longitudinal vertical section of a machine embodying my improvement.

Figure 2 is a transverse vertical section of the same.

Figure 3 is a view of the surface of the corrugated plate.

Figure 4 is a metallic frame or spider.

Similar letters indicate like parts in the several figures.

The object of my invention is to produce a machine which will remove the husks or integuments from the coffee-berry in an efficient and expeditious manner; and the invention consists in the employment of an endless band or apron, formed of a series of serrated or corrugated metal plates, joined or linked together so as to be rotated upon drums arranged one at each end of the machine, in combination with a serrated or corrugated metallic plate, so arranged in relation to the endless band that the berries of coffee will be made to pass between the two, and by abrasion be deprived of the integument or husk with which they are covered. And the invention also consists in the employment, in combination with the serrated plates, both stationary and rotating, of elastic bearing-pieces, for the purpose of allowing the same to yield or give, in the event of any hard substances or particles of larger size than the coffee-berry passing into the machine. The invention also consists of a metallic frame or spider, for sustaining the upper portion of the endless belt during its operation.

Referring to the drawings, *a a* represents the frame of a hulling-machine, in which are supported, at either end and at different heights, the drums *b c*. Supported upon these drums is an endless band, formed of a series of metallic plates secured together in such a manner as to admit of the band being freely moved by the drums as the latter rotate. The outer faces of the said plates are serrated or corrugated. The upper portion of the endless band *d* is supported in a position parallel with the upper plate by means of a metallic frame or spider of the form shown in fig. 4, and consisting of two parallel longitudinal bars *h h*, attached to arms *i i*, resting upon the sides of the frame, as shown in fig. 2. Underneath the ends of the arms *i i* are placed pieces or blocks of India rubber *r' r'*. Over the upper portion of the endless band *d* is placed a metallic plate, *e*, serrated or corrugated on its under surface, as shown in fig. 3, and extending nearly the whole length of the upper surface of the endless band *d*. The said plate is formed with sides *e'*, projecting downwards on each side of the upper portion of the band *d*, as shown in fig. 2, for the purpose of preventing the berries from escaping over the sides of the band. The plate *e* is supported in the upper part of the machine by means of rods *o* and screw-nuts *n*, in connection with arched or curved cross-bars *g*, extending across the top of the frame.

Between projections, *f*, on the upper part of the plate *e*, and the cross-pieces *g*, are placed blocks of India rubber, *r*, upon the rods *o*, for the purpose of allowing a yielding motion to the plate *e*, in case any hard foreign substance of larger size than the coffee-berries should pass into the machine.

By means of the nuts *n n* the plate *e* may be adjusted to increase or diminish the space between it and the endless band *d*. The endless band *d* is put in motion by the application of any suitable power to the drum *c*, which is provided with teeth or projections fitting between the plates of which the band is composed.

At one end of the machine is a hopper, provided with an adjustable plate, *m*, by which the amount of berries to be fed to the endless band is regulated.

What I claim as new, and desire to secure by Letters Patent, is—

1. The combination of the endless band *d*, composed of serrated metal plates, with the serrated plate *e*, provided with the sides *e'*, substantially as and for the purpose set forth.

2. I claim the combination of the endless band *d*, the supporting-frame *h i*, and the elastic bearings *r'*, as described.

In testimony whereof, I have signed my name to this specification in the presence of two subscribing witnesses.
